UNITED STATES PATENT OFFICE.

HENRY SELBY HELE-SHAW AND FRANCIS LEIGH MARTINEAU, OF LONDON, ENGLAND.

ROTARY PUMP OR MOTOR.

1,250,170.

Specification of Letters Patent. Patented Dec. 18, 1917.

Application filed January 24, 1916. Serial No. 73,989.

To all whom it may concern:

Be it known that we, HENRY SELBY HELE-SHAW and FRANCIS LEIGH MARTINEAU, both subjects of His Majesty the King of Great Britain, and residents of London, England, have invented certain new and useful Improvements in Rotary Pumps or Motors, of which the following is a specification.

This invention relates to improvements in rotary pumps or motors and has reference to pumps or motors of the type wherein a cylinder body rotates about a stationary central valve and the pistons within the cylinders derive their movement of reciprocation by coöperation without definite attachment with an eccentrically situated ring, which ring revolves or floats around in company with the cylinder body in the manner disclosed in the specification of prior Letters

20 Patent, granted to Henry Selby Hele-Shaw, No. 1,077,979.

The object of the present invention is to simplify the construction to reduce the cost of manufacture and render certain of the 25 internal parts interchangeable and more readily accessible and to eliminate noise. The invention consists of a particular construction and arrangement, the primary feature of which is the use throughout of plain 30 bearings which involves special means of effecting lubrication. Another feature consists in the provision of a removable fitment carrying the inlet and outlet pipes and the usual make up valves, and this involves the 35 provision of a central valve designed to accommodate this fitment.

Another feature consists of the method of making the central valve designed for simplicity and cheapness of manufacture. The 40 invention is illustrated in the accompanying drawings wherein Figure 1 is a front elevational view partly in section of a pump or motor constructed in accordance with and embodying the essential features of the invention.

Fig. 2 is an end elevational view on line A—A of Fig. 1, Fig. 3 is an end section through the line B—B of Fig. 1.

Fig. 4 is an outside elevation of the central 50 valve, and Fig. 5 is a transverse section thereof. Fig. 6 is a detail view showing more particularly the parts 6, 7, 8 and 9.

Referring to these drawings the numeral 1 55 designates a central cylindrical casing member and this casing member is closed upon either side by means of circular side walls 2

provided with stuffing box bearings 3 to support the central shaft 4 and glands or stuffing boxes 6 and 7 may be provided if necessary to accommodate and guide the cylindrical casing which may conveniently have a central rod 8 and parallel side rods 9. These glands 6 and 7 are preferably arranged lying in the same direction and immediately opposite one another so that the side walls of 60 the casing are interchangeable, that is to say, by turning the right hand side wall around, it can be arranged on the left hand side and similarly, the left hand side wall can be arranged upon the right hand side if desirable. 65 The part 19 is a sliding block which carries the bearings in which the stroke controlling drum 11, inclosing the cylinder body is mounted. The member 11 and the cylinder body rotate together but whereas the cylinder body is mounted upon a fixed center, the 70 valve, the drum 11 is pushed bodily from side to side by the member 8 so as to vary the stroke of the piston, this drum further controlling the direction of delivery. These 75 outer side walls are provided with wells or oil receiving ridges 10 adapted to catch lubricant which is delivered to them in the form of spray as the eccentric ring or drum 11 rotates in the manner well known. The 80 eccentric ring, which is usually provided with means such as the rods 8, 9 before referred to, whereby its position relative to the central axis of the machine can be varied to vary the stroke of the pistons of the machine, is mounted to rotate upon plain bearings 12 preferably faced with white metal 85 90 95 100 105 110

13 and at one or more positions a felt or other pad 14 extends through the white metal into wiping contact with the surface which rotates against it and this pad may be kept in position by means of the spring 15 and it is continuously charged with lubricant by means of holes or passages 16, 17 leading to it from the wells or oil storage ridges 10 formed as aforesaid in the casing walls 2, these wells or ridges acting as a continual oil supply. The particular arrangement adopted in respect of each of the pads 14 is to provide a passage or passages 17 leading from the oil wells or ridges 10 to a recess 18 cut in the upper edge or surface of the sliding member 19 which carries the bearing. The passage or passages 16 lead from this recess to the pad 14 and effectually lubricate it as will be readily understood upon reference to Fig. 3 of the drawings. It

will be understood that the recesses 18 are of such a length that there is communication with the passages 17 in all positions of the sliding block 19. This really means that the recesses should be slightly longer than the maximum travel of the block 19 to impart maximum eccentricity to the stroke controlling drum 11 in either direction. Of course with a machine where there is a fixed eccentricity and thus a fixed stroke for the pistons, a continuous passage or passages 16 can be provided leading directly from the oil well or ridge to the pads and the recesses 18 would be unnecessary.

15 The pistons 20 coöperate with tracks 21 upon the eccentric ring or drum 11 through rollers 22 which are mounted upon pins 23 passing through the pistons and through slots 24 in the walls of the cylinders 25. 20 These rollers 22 are plain bearing rollers brushed or faced with white metal 26 and their bearings are lubricated preferably by means of channels 27 having branches 28 cut or drilled in the pins and the lubricant is 25 delivered to these channels from the cylinders 25 of the machine—where oil is the working fluid as is usually the case with this type of apparatus—small holes 29 leading from the pistons to the passages aforesaid 30 in the pins. The rollers aforesaid are preferably so formed as to have wider bearing surface upon the pins than their peripheral surfaces where contact with the stroke controlling ring occurs as is illustrated in Fig. 35 1 of the drawings.

The central valve 30 is constructed from a cylindrical member which is turned to the required size and shape and inlet and outlet passages 31 and 32 are drilled and slots 40 33 are machined out to form ports about which the cylinders rotate. The end 34 of the valve is coned and the fitment 35 receives it. This fitment carries inlet and outlet pipes 36 and 37 and the usual leakage 45 make-up valves 39, a pipe 40 leading from a make-up tank to the chamber 41. It will be understood by those conversant with this type of apparatus that any leakage in the system is automatically made-up from the 50 make-up tank by suction through the valves 39, one or the other of which is always in connection with the suction side of the apparatus. The make-up valves 39 are duplicated and one communicates with a groove 55 42 cut in the valve, which groove is in communication with the valve passage 31, and the other leads to the chamber 43 which is in communication with the other valve passage 32 which is drilled right through the 60 end 34. Thus one or other of the make-up valves 39 is in communication with whichever of the passages 31 and 32 is the suction passage at the moment. It should perhaps be here mentioned that while in the foregoing description certain passages and pipes

have been referred to as "inlet" and "outlet" 70 passages and pipes respectively, it will be understood that since machines of this type are usually reversible, those pipes and passages designated "inlet" will become "outlet" and vice versa if the machine is reversed. The operation of this type of apparatus is now so well known as to require no further description and suffice it to say that the cylinder body is keyed or clutched 75 at 44 to the driving shaft 4 by which the cylinders are continuously rotated and the pistons 20 reciprocate with a stroke dependent upon the degree of eccentricity imparted to the stroke controlling ring or drum 11, 80 and the direction of inlet and discharge will depend upon which side of the axis the drum 11 is adjusted. The machine hereinbefore described and illustrated is specially designed as a pump but it will be understood 85 that the invention is equally applicable in the case of motors, and in fact the machine described and illustrated would operate as a motor if fluid under pressure were applied to one or other of the passages 31 90 and 32 of the control valve.

What we claim and desire to secure by Letters Patent is:

1. A hydraulic machine comprising a central valve, a cylinder body rotatable upon 95 said valve and having cylinders formed therein, openings in the cylinders coöperating with ports in the valve, pistons operating in said cylinders, a stroke controlling ring inclosing the cylinders and coöperating with 100 and effecting reciprocation of the pistons, plain bearings upon which said stroke controlling ring rotates, oil storage reservoirs in the casing and oil passages leading from said oil storage reservoirs to lubricate said 105 bearings, substantially as specified.

2. A hydraulic machine comprising a central valve, a cylinder body rotatable upon 110 said valve and having cylinders formed therein, openings in the cylinders coöperating with ports in the valve, pistons operating in said cylinders, a stroke controlling ring inclosing the cylinders and coöperating with and effecting reciprocation of the 115 pistons, plain bearings upon which said stroke controlling ring rotates, oil storage reservoirs in the casing, absorbent pads located in openings in said plain bearings, passages leading from said oil storage reservoirs to said pads for lubricating said 120 bearings, substantially as specified.

3. A hydraulic machine comprising a central valve, a cylinder body rotatable upon 125 said valve and having cylinders formed therein, openings in the cylinders coöperating with ports in the valve, pistons operating in said cylinders, a stroke controlling ring inclosing the cylinders and coöperating with and effecting reciprocation of the pistons, plain bearings upon which said stroke 130

controlling ring rotates, oil storage reservoirs in the casing, absorbent pads located in openings in said plain bearings, springs tending to press said pads against the surface to be lubricated whereby wiping contact is steadily maintained, passages leading from said oil storage reservoirs to said pads for lubricating said bearings, substantially as specified.

4. A hydraulic machine comprising a central valve, a cylinder body rotatable upon said valve and having cylinders formed therein, openings in the cylinders coöperating with ports in the valve, pistons operating in said cylinders, a stroke controlling ring inclosing the cylinders and coöperating with and effecting reciprocation of the pistons, plain bearings upon which said stroke controlling ring rotates, sliding blocks carrying said bearings, guides on the casing walls between which said blocks slide, oil storage recesses above the upper of said guides, passages leading from said storage recesses to recesses in the upper edges of said sliding blocks and passages in the sliding blocks leading from the recesses in their upper edges to the bearings to be lubricated, substantially as specified.

5. A hydraulic machine comprising a central valve, a cylinder body rotatable upon said valve and having cylinders formed therein, openings in the cylinders coöperating with ports in the valve, pistons operating in said cylinders, pins upon the outer ends of said pistons, rollers rotatable on the pins, plain metal bearings in said rollers, passages in the pins leading to the bearings, pas-

sages in the pistons leading from the interior of the cylinders to the passages in the pins whereby working fluid from the interior of the cylinders is conveyed to the bearings of the rollers, a stroke controlling ring inclosing the cylinders and coöperating with and effecting reciprocation of the pistons, plain bearings upon which said stroke controlling ring rotates, oil storage reservoirs in the casing, and oil passages leading from said oil storage reservoirs to lubricate said bearings, substantially as specified.

6. A hydraulic machine comprising a central valve, a coned extension on said valve, a removable fitment receiving said extension, inlet and outlet pipes carried by said fitment, a make-up tank attached to said fitment, non-return make-up valves carried by said fitment and depending into said make-up tank, a cylinder body rotatable upon said valve and having cylinders formed therein, openings in the cylinders coöperating with ports in the valve, pistons operating in said cylinders, a stroke controlling ring inclosing the cylinders and coöperating with and effecting reciprocation of the pistons, plain bearings upon which said stroke controlling ring rotates, oil storage reservoirs in the casing, and oil passages leading from said oil storage reservoirs to lubricate said bearings, substantially as specified.

In testimony whereof we affix our signatures in presence of two witnesses.

HENRY SELBY HELE-SHAW.
F. LEIGH MARTINEAU.
